UNITED STATES PATENT OFFICE.

FRANK L. WRIGHT, OF CHICAGO, ILLINOIS, ASSIGNOR TO THE LUXFER
PRISM PATENTS COMPANY, OF SAME PLACE.

DESIGN FOR A PRISM-PLATE.

SPECIFICATION forming part of Design No. 28,003, dated December 7, 1897.

Application filed October 23, 1897. Serial No. 656,227. Term of patent 14 years.

To all whom it may concern:

Be it known that I, FRANK L. WRIGHT, a citizen of the United States, residing at Chicago, in the county of Cook and State of Illinois, have invented a certain new and original Design for Prism-Plates, of which the following is a specification.

My invention relates to designs for prism-plates.

Figure 1 is a plan view of a prism-plate embodying my design. Fig. 2 is a cross-section therethrough.

A A are surface areas comparatively uniform and formed by the lines of separation B B on the surface of the prism-plate. C C are prisms on the opposite side.

D D are lines which constitute designs along a band of lower areas, E E lines which form designs along an upper band of areas, and F F lines which constitute designs upon intermediate areas. The designs on intermediate areas are arranged so as to form a distinct and separate pattern or design on each

such area, such patterns or designs being uniform. The result, as indicated, is a distinctly-ornamented bar or band across the upper part and another bar or band across the lower part, with a field ornamented by uniform ornaments, giving a sort of mosaic effect.

The essential feature of my design is found in a prism-plate comprising an extended body with prisms on one side, lines of separation which divide the other surface into a series of areas, and a band of such areas distinctly ornamented across the top and another across the bottom, with a field of surface areas uniformly ornamented and distinguished from the band.

I claim—

A design for a prism-plate, substantially as shown and described.

FRANK L. WRIGHT.
